US0D1076660S

(12) **United States Design Patent** (10) **Patent No.:** **US D1,076,660 S**
(45) **Date of Patent:** **** May 27, 2025**

(54) **BRACKET**

(71) Applicant: **DiversiTech Corporation**, Duluth, GA (US)

(72) Inventors: **Thomas Wouters**, Duluth, GA (US); **Dale Harrison**, Duluth, GA (US); **Chris Willette**, Duluth, GA (US)

(73) Assignee: **DiversiTech Corporation**, Duluth, GA (US)

(**) Term: **15 Years**

(21) Appl. No.: **29/882,774**

(22) Filed: **Jan. 18, 2023**

Related U.S. Application Data

(63) Continuation of application No. 17/300,323, filed on Jul. 15, 2022, now abandoned, and a continuation-in-part of application No. 17/300,324, filed on Jan. 19, 2022, now abandoned.

(57) **CLAIM**

An ornamental design of a bracket, as shown and described.

DESCRIPTION

FIG. 1 is a perspective view of a first embodiment of a bracket;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof.

FIG. 8 is a perspective view of a second embodiment of the bracket;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

Broken lines shown in drawings illustrate portions of the bracket that form no part of claimed design.

1 Claim, 8 Drawing Sheets
